MOTOR COMPRESSOR

Raul Pateras Pescara, Paris, France

Application January 5, 1933, Serial No. 650,350
In France July 5, 1932

5 Claims. (Cl. 230—56)

The present invention relates to motor compressors of the type in which two compressing pistons are adapted to move in opposite directions under the direct action of the internal combustion 5 of a fuel.

The object of the present invention is to provide a motor compressor of that type which is more simple, comprises a lesser number of parts, and is easier to manufacture.

10 A preferred embodiment of my invention will be hereinafter described with reference to the accompanying drawings, given merely by way of example, and in which:

Fig. 1 is an elevational view, partly in section, 15 of a motor compressor according to the present invention;

Fig. 2 is a horizontal axial section of said motor compressor;

Fig. 3 is a composite view, the right hand side 20 of which is a section on the line AB of Fig. 1, and the left hand side of which is a section on the line CD of Fig. 1.

Fig. 4 is an elevational view, partly in section, of a complete motor compressor.

25 According to my invention all the stationary parts of the motor compressor form a unit 1 which comprises:

(a) Three cylinders (compression cylinder 101 provided with longitudinal grooves 11 and connected with delivery pipe 105 through outlet 30 valves 103, motor cylinder 102, the ends of which are provided with cooling fins 24 and with a piece 25 screwed thereon and fitted with packing rings 26, and another compression cylinder 106, similar to cylinder 101);

(b) A chamber 21 carried by each compression cylinder, connected with the atmosphere through openings 20 provided with air inlet valves 19, and connected with the inside of the compression 40 cylinder through a port 22;

(c) A casing 104 inclosing a chamber 12 having a bottom closure 13 forming the scavenging air reservoir, which extends along the whole length of the compressor and is connected with motor cylinder 102 through ports 14;

(d) A chamber 15 carried by each compression cylinder 101, connected with the inside of said cylinder through ports 30 and with chamber 12 through ports 16 provided with valves 17;

50 (e) Two longitudinal external recesses 8 provided on either side of said casing 104, closed on the outer side by plates 9, and connected with chamber 15 through ports 18; said recesses are disposed along grooves 11 of compression cylinder 55 101.

Two pistons such as 2 are fitted in said cylinders in such manner that their outer ends reciprocate in the compression cylinders respectively and their inner ends (of reduced section) reciprocate in motor cylinder 102. The inner faces of the enlarged ends of the pistons are provided with an annular recess 27 for receiving the end of the motor cylinder.

The pistons are connected together through rods 3 pivoted at one end about journals 4 provided on the pistons, and at the other end to cranks 5 pivoted about journals 6 fitted in unit 1.

Journals 4 also carry sliding members 7 adapted to reciprocate in a piston-like manner in guiding recesses 8. The inner face of said sliding members is provided with a plate 10 adapted to cover the portion of groove 11 located between said journal 4 and the inner end of said groove.

The operation of the apparatus is as follows:

The piston starts from its innermost position. 20 It compresses air in the compression cylinder until valves 17 open so that air from the compression cylinder is discharged into the scavenging air reservoir 12 through ports 30, chamber 15, and ports 16. As the piston further moves it closes ports 11 and 30 so that there is no longer any connection between the compression chamber and chamber 15. But pistons 7 keep driving compressed air into reservoir 12. Piston 2 now compresses air in cylinder 101. It comes to cover port 22 so that there is no longer any connection between cylinder 101 and chamber 21. Toward the end of the stroke the outlet valves 103 open and air is discharged into delivery pipe 105. At the end of the outstroke said outlet valves close and the compressed air remaining in the cylinder drives back the piston. When said piston uncovers port 22, valves 19 open and fresh air is admitted into the cylinder.

While I have described what I deem to be a preferred embodiment of my invention, it should be well understood that I do not wish to be limited thereto as there might be changes made in the arrangement, disposition and form of the parts without departing from the principle of my invention as comprehended within the scope of the appended claims.

What I claim is:

1. A motor compressor of the type described comprising in combination, a motor cylinder, two compression cylinders integral with said motor cylinder and disposed on opposite sides thereof and coaxially therewith, two opposed pistons the inner ends of both of which reciprocate in the motor cylinder and the outer ends of which re- 50 55

ciprocate in the compression cylinders respectively, a guide for said pistons integral with said cylinders, and a casing integral with said cylinders and surrounding them so as to form a reservoir for the compressed air for scavenging the motor cylinder.

2. A motor compressor of the type described comprising in combination, a motor cylinder, two compression cylinders integral with said motor cylinder and disposed on opposite sides thereof and coaxially therewith, each of said compression cylinders being provided with two diametrically opposed longitudinal slots, two opposed pistons the inner ends of which reciprocate in the motor cylinder and the outer ends of which reciprocate in the compression cylinders respectively, two diametrically opposed journals carried by each of said pistons and engaging said slots, two guides for said journals integral with said compression cylinders, sliding members adapted to act in piston like manner in said guides pivoted about said journals,

and a casing integral with said cylinders and surrounding them so as to form a reservoir for the compressed air for scavenging the motor cylinder.

3. A motor compressor according to claim 2 further comprising two journals carried by said motor cylinder, two opposed cranks pivoted about each of said journals, and connecting rods articulated at one end to one of said cranks and pivoted at the other end about the first mentioned journals respectively.

4. A motor compressor according to claim 1 further comprising check valves for connecting the said compression cylinders with said scavenging reservoir, and a chamber for said valves integral with said compression cylinders.

5. A motor compressor according to claim 2 further comprising check valves for connecting said compression cylinders with said scavenging air reservoir, and a chamber for said valves integral with said compression cylinder.

RAUL PATERAS PESCARA.
